UNITED STATES PATENT OFFICE.

GEORGE L. BIDWELL, OF RIEGELSVILLE, PENNSYLVANIA.

HARD-STOCK WHIPPER.

1,352,866.

Specification of Letters Patent. Patented Sept. 14, 1920.

Application filed March 1, 1920. Serial No. 362,326.

To all whom it may concern:

Be it known that I, GEORGE L. BIDWELL, a citizen of the United States of America, residing at Riegelsville, in the county of Bucks and State of Pennsylvania, have invented a new and useful Hard-Stock Whipper, of which the following is a specification.

My invention relates to improvements in devices or appliances designed for removing the dust and dirt from what is known as "hard stock," such as rags, burlap, gunny, rope, hemp, jute, and sisal, used in the manufacture of paper or of pulp from which paper is made, and consists of an endless carrier for the stock, and one or more baffles and adjacently-located rotary, winged paddles, all suitably inclosed, together with such other parts and members as may be necessary or desirable in order to render the appliance or whipper complete and serviceable, all as hereinafter set forth.

This whipper is designed especially for use in connection with my new process of making pulp for paper, for which I have filed an application for Letters Patent of the United States on even date herewith, Serial No. 362,325.

One object of my invention is to afford means for removing the foreign substance or matter from hard stock with the minimum amount of waste. Machines of this character in the past have removed with the foreign matter much valuable lint, even as high as 8% in weight of the original stock being lost by such machines in not infrequent cases. With my machine or appliance the waste is almost negligible, wherefore said appliance is economical in the handling of the stock.

Another object is to produce a continuous-motion appliance of this character, so that the cleaning operation can proceed without interrupting, to the end that an important saving in time is effected.

A further object is to provide a whipper which is simple in construction and operation, and comparatively inexpensive as well, so that another saving in expense is experienced.

Other objects and advantages will appear in the course of the following description.

I attain the objects and secure the advantages of my invention by the mechanism illustrated in the accompanying drawings, in which—

Figure 1 is a top plan of a whipper which embodies a practical form of my invention, the inclosure or whipper-house being in section, thus showing the mechanism within the same in full; Fig. 2, a side elevation of said whipper, the near side of said whipper-house being removed, and, Fig. 3, a cross section through said whipper, taken on lines 3—3, looking in the direction of the associated arrow, in Fig. 2.

The section through the whipper-house in the first view is taken on lines 1—1, in Fig. 2. Portions of the whipper are broken out in Figs. 1 and 2 in order to economize space.

Similar reference numerals designate similar parts throughout the several views.

The whipper mechanism is inclosed in a whipper-house 2 of any suitable construction. This whipper-house supports the operated mechanism and associated elements 75 of the machine, and confines the dust produced by said mechanism and elements from the hard stock which is fed to the mechanism and passed through said house. Said dust is withdrawn from the top of the whipper-house 2 by means of a forced draft 80 created in the customary manner. The dust escapes through a flue 4 at the front end of a raised portion 5 of the whipper-house, it being to said flue that the suction is applied 85 which removes the dust from said house.

The right-hand end of the whipper as it stands in the drawings is the front end, and there is an opening 6 in the whipper-house at such end. An inclined table 7 extends 90 into the opening 6. The hard stock to be whipped is placed on or discharged onto the table 7 and slides down the same onto an endless apron 8. In the opposite or rear end of the whipper-house near the bottom is 95 another opening 9.

The apron 8 is supported on two rollers 10 having shafts 11 and 12 which are journaled in the sides of the whipper-house. The rollers 10 and the apron 8 are driven 100 by a pulley 13 secured on the rear terminal of the shaft 11, which terminal extends beyond the backside of the whipper-house, and by a belt (not shown) applied to said pulley. The upper reach of the apron 8 105 travels in the direction indicated by the associated arrow in Fig. 2. The table 7 discharges onto the apron 8 directly above the front roller 10.

A slatted apron 14 is supported on rollers 110

15—15 which are mounted on shafts 16—16 that are journaled in the sides of the whipper-house 2 below the horizontal plane of the shafts 11 and 12, the arrangement being such that said apron extends beneath said roller 12 and the apron 8 at the rear end. Thus it is seen that the apron 8 is located in the forward part of the whipper-house and the apron 14 in the rearward part 10 of said house. A slotted drawboard 17 is supported on the apron 14 and is of such length, when in proper position on said apron, as to extend beneath the rear end of the apron 8. The drawboard 17 can be withdrawn from the whipper-house and replaced therein through the opening 9.

The above-mentioned apron and drawboard are old and well-known in the art.

Rigidly attached to the sides of the whipper-house inside are two transverse, vertical members 18 which are termed baffles. These are arranged one behind the other over the apron 8.

Behind each baffle 18 is a shaft 19 which 25 is journaled in the sides of the whipper-house and projects beyond the backside thereof. Securely mounted on each shaft 19 within the whipper-house is a paddle 20, and securely mounted on the terminal of 30 such shaft which protrudes from said house behind is a pulley 21. The two pulleys 21 are driven by belts (not shown), and in turn drive the shafts 19 and the paddles 20, the direction of rotation being indicated by the 35 associated arrows in Fig. 2. The paddles 20 consist merely of a pair of hubs mounted on one of the shafts 19 and having oppositely-disposed, downwardly-extending arms connected at their outer ends by wing pieces 40 22—22, the latter preferably being on the front, in the direction of rotation, of said arms, as shown in the drawings. The paddles 20, like the baffles 18, are over or above the apron 8, and said paddles are in operative 45 position relative to both said baffles and apron, or in position to sweep portions of stock from said apron and throw it against said baffles. The paddles 20 are revolved rapidly so that they throw the stock against 50 the baffles 18 with great force.

In practice, after the drawboard 17 is run in on the apron 14 until the forward end of said drawboard is beneath the rear-end portions of the apron 8, power is applied to the 55 pulleys 13 and 21 and the apron 8 and paddles 20 are set in motion. Stock is now fed to the apron 8 from the table 7, and as said stock is carried under the rapidly-revolving paddles 20 the latter catch up portions 60 of the same and dash said portions violently against the baffles 18. The apron 8 travels slowly so that usually the two paddles are able to throw against the baffles all the stock that is fed to said apron, and 65 each paddle even is able to handle all of said

stock, with the result that the stock is subjected twice to the whipping action of the machine.

When the stock strikes the baffles some of 70 said stock falls down in front of said baffles directly on to the apron 8 below, and some of it is carried over and around with the paddles to be dashed against said baffles again. Thus it is seen that the stock receives a very thorough whipping by the time it 75 arrives at the rear end of the apron 8. From the rear end of the apron 8 the stock falls onto the drawboard 17. The stock continues to accumulate on the drawboard until the latter is full, when it is drawn out through 80 the opening 9 and its contents is dumped into a suitable receptacle or receiver, after which the drawboard is returned to place on the apron 14 and with the forward end of the drawboard beneath the rear end portions 85 of the apron 8. The movable character of the apron 14 facilitates the operation or manipulation of the drawboard in the manner described.

During the operation of the whipper, the 90 lighter portions of the foreign matter shaken or whipped out of the stock are drawn out through the flue 4, while the heavier particles of such matter pass through the slots in the drawboard 17 and 95 the openings in the slatted apron 14 to the floor of the whipper-house 2.

In the event one passage through the whipper be not sufficient to eliminate the dust or foreign matter from the stock, the 100 latter can be run through the whipper a second time, or as many times as may be desired.

Obviously the number of baffles and paddles may vary.

The action on the stock when thrown against the baffles by the paddles is of a 105 nature to shake out of such stock the foreign matter therein, without a sufficient degree of violence to dismember the stock or even 110 fray or otherwise disintegrate the same.

Closures may be provided for the openings 6 and 9 if desired or found to be necessary.

What I claim as my invention, and desire 115 to secure by Letters Patent, is—

1. In a hard-stock whipper, a conveyer for the stock, a rotary paddle in operative relation to said conveyer, and a baffle above 120 said conveyer and behind and extending below the horizontal plane of the axis of said paddle.

2. The combination, in a hard-stock whipper, with a whipper-house, an apron in said house, and means to drive said apron, of a 125 rotary paddle in said house above said apron, and a fixed baffle in said house behind said paddle and extending below the horizontal plane of the axis thereof.

3. The combination, in a hard-stock whip- 130

per, with a whipper-house, an apron in said house, means to drive said apron, a perforated apron mounted to travel in said house, and a slotted drawboard receivable on said last-mentioned apron, the arrangement being such that said drawboard can be pushed forward beneath said first-named apron at the rear end of the latter, of a rotary paddle in said house above said first-named apron, and a baffle in said house behind said paddle.

4. In a hard-stock whipper, a conveyer for the stock, a shaft, a paddle mounted on said shaft above said conveyer, said pad-

dle consisting of hubs with oppositely-extending arms, and wing pieces connecting said arms at their outer terminals, open spaces being left between said shaft and said wing pieces, and a baffle behind said paddle, parallel with the axis of the latter, and approximately perpendicular to the main course of said apron, said baffle extending below the horizontal plane of said axis.

GEORGE L. BIDWELL.
